CLAIM

The ornamental design for a handset, as shown and described.

DESCRIPTION

FIG. 1 is a front perspective view of a handset showing our new design;

FIG. 2 is a front view thereof;

FIG. 3 is a right side view thereof;

FIG. 4 is a left side view thereof;

FIG. 5 is a bottom view thereof;

FIG. 6 is a top view thereof; and,

FIG. 7 is a rear view thereof.

The broken lines that show the outermost periphery of the speaker feature in FIGS. 1 and 2 form a boundary of the claimed design. The broken line immediately within the perimeter of the double solid line in FIG. 7 forms a boundary of the claimed design. All other broken lines are directed to environment and are for illustrative purposes only. The broken lines, and the unshaded regions defined by broken lines, form no part of the claimed design.
